UNITED STATES PATENT OFFICE.

FOLKE W. WESTON, OF NEW YORK, N. Y.

PRINTER'S PLATE-HOLDING DEVICE.

1,073,378.

Specification of Letters Patent. Patented Sept. 16, 1913.

Application filed May 4, 1911. Serial No. 625,056.

To all whom it may concern:

Be it known that I, FOLKE W. WESTON, a citizen of the United States, and resident of the city of New York, borough of Brooklyn, county of Kings, and State of New York, have invented certain new and useful Improvements in Printers' Plate-Holding Devices, of which the following is a specification.

10 This invention relates to printers' plate holding devices intended for holding printing plates in position on the base.

One important adaptation of this invention is in printing work where a number of colors are used which require a number of 15 separate impressions to be made upon the paper so that successive impressions made by different plates will register one with the other. In order to produce the desired results it is necessary to retain the several plates always in a fixed relation to each other. The device for holding the plates in position on the base is known as a "printer's hook" and the object of this invention is to 20 provide such a hook of peculiar and novel construction and also to provide certain novel features for the construction of the base upon which one or more plates are held by the hooks, all of which will be more 25 fully explained and the advantages and novel features thereof pointed out in connection with the description of the embodiment of the invention as illustrated in the 30 accompanying drawings.

35 In the drawings like parts in the several views have been given the same reference numerals.

Figure 1 is a plan view of a base with a plate secured in position thereon by means 40 of a number of these printers' hooks. Fig. 2 is an enlarged sectional view on the line 2—2 of Fig. 1. Fig. 3 is an enlarged view of the end of one of the slots or channels of the base, showing the hook locked in position. 45 Fig. 4 is a view similar to Fig. 3, showing the hook partially inserted in the slot of the base. Fig. 5 is a side elevation of the hook. Fig. 6 is a plan view of the hook. Fig. 7 is a detailed view of one form of handle for 50 locking and adjusting the hook in position; Fig. 8 is a sectional end view of the hook on the line 8—8 of Fig. 6. Fig. 9 is a plan view of a modified form of hook. Fig. 10 is a sectional view of a portion of the base, 55 showing the hook in position therein. Fig.

11 is an end view of the slot or channel of the base and hook shown in Fig. 10.

In the construction shown in Figs. 1 to 8, inclusive, a base is shown at 1 and printing plate 2 positioned thereon. The base 1 is 60 provided with a number of slots or channels which are T-shaped and preferably extending diagonally across the base 1. Positioned in the overhanging side walls of the slots or channels 3 are one or more racks 4, which 65 are preferably two in number and constructed of hardened steel and arranged on opposite sides of the slots to serve also as a bearing under which the hook is secured. This will be explained more fully herein- 70 after. The hook body is constructed with a top or upper portion 5 and a bottom or lower portion 6, each comprising a single piece of material and extending the full length of the hook body and constituting 75 upper and lower main body members, these members being secured together by vertically extending portions. The jaw 7 is preferably formed integral with the top portion 5 and in angular position thereon corre- 80 sponding to the angular position of channels or slots 3 in the base 1. The bottom portion 6 is cut away to receive the operating members between the vertically extending portions or ends which are joined by a horizontal connecting member or portion preferably formed integral therewith. This horizontal connecting member is located be- 85 tween the screw operating means and the lower wall of the slotted portion when the 90 hook is in place therein. The locking or swinging members 8 are rotatively mounted in either end of the hook in the manner shown in Figs. 5, 6 and 8, so that when the hook is in position in a slot of the base 1 a 95 quarter turn of the locking member will lock or unlock the same. The locking mem- bers 8 are turned by means of a sleeve 9 which also forms a bearing for the same and which is provided with a collar 10 at the 100 opposite or upper end thereof. The upper end of this sleeve is provided with a square socket 11 into which the handle 12 is in- 105 serted and by means of which the locking member is turned. This handle may be of the angular form, shown at 12 in Figs. 3 and 4, or may be of the straight form, as shown at 12' in Fig. 7. A pin 13 in the bottom portion 6 of the hook is positioned so as to enter a slot 14 in the sleeve 9 and provides 110

a stop for limiting the rotary movement of the locking member 8 to the necessary quarter turn for locking and unlocking. A bevel gear 15 operates a worm or screw operating member 16 both of which are rotatively mounted in the bottom portion 6 of the hook, as shown in Figs. 5 and 6. The bevel gear 15 is provided with a square socket into which the handle 12 or 12' may be inserted for rotating the same. The rotation of the bevel gear 15 rotates the worm 16 which engages the racks 4 in the base 1 and by this means the hook is adjusted to hold the printing plate 2 in position upon the base 1. In addition to the means provided for adjusting the hook in position as just described, the same is also provided with the locking members 8, which are turned by the handle 12 and caused to engage beneath the racks 4, thus locking or holding the hook in position in the slot, as shown in Fig. 3. The locating and arrangement of the racks 4 upon the opposite sides of the slots, provides for the locking members 8 to engage beneath these racks and as the same are preferably constructed of hard steel a very secure fastening means is thus provided which is not destroyed by the ordinary wear so as to render the same useless for this purpose. The teeth of the companion racks are preferably arranged on the inner edges or adjacent faces of the racks and the underside portions of the racks are preferably flat so as to be engaged by the locking means which hold the hook in place in the slot. Thus it will be observed that the racks constitute overhanging portions having teeth at their adjacent faces and flat surfaces at their lower sides.

In the modifications shown in Figs. 9 to 11, the base 21 is provided with slots 23 similar to the slots in the base 1. The racks 24 are similarly positioned in these slots but the teeth of the racks are cut away at their lower side so that the locking members 28 of the hook engage beneath the body portion of the rack and not against the teeth, thus providing a more substantial locking means of greater durability. The top portion 25 and the bottom portion 26 of the hook are fastened together and the jaw 27 is formed integral with the top portion 25. The locking members 28 are each provided with a sleeve 29 and collar 30 and are mounted for rotative movement by means of a square socket 31 in the sleeve 29. The pin 33 mounted in the bottom portion 26 engages in the slot 34 in the sleeve 29 to limit the rotative movement of the locking member 28 to a quarter turn for its locked or unlocked positions. The bevel gear 35 is mounted for rotative movement in the bottom portion 26 of the hook and is so constructed as to be inclosed on either side thereof in the hook so that the same is protected against injury or

from becoming gummed up from the accumulations in the slot. The bevel gear 35 operates the worm gear 36, which is mounted for rotative movement in the bottom portion 26 of the hook so as to engage the teeth of the racks 24 when the hook is placed in position in one of the slots in the base 21. This latter construction shown in Figs. 9 to 11 provides a compact hook construction in which the bevel operating gear is inclosed and protected and also provides a smaller gear for fine adjustment.

As many changes could be made in the above construction and many apparently widely different embodiments of my invention designed without departing from the scope of the appended claims, I intend that all matter contained in the above description or shown in the accompanying drawings shall be interpreted as illustrative merely of an operative embodiment of my invention and not in a limiting sense.

What I claim is:

1. A printer's plate holding device comprising, in combination, a base provided with one or more slots in one face thereof, racks projecting inwardly from the opposite side walls of said slots having smooth surface portions at their under sides, the teeth of said racks being located on adjacent faces thereof, and a hook provided with means for engaging said racks for progressive movement and also with locking means independent of the hook moving means for engaging said smooth portions beneath said racks.

2. A printer's plate holding device comprising, in combination, a base provided with one or more T-shaped slots in one face thereof, racks projecting inwardly from the opposite side walls of said slots, having smooth surface portions at their under sides, the teeth of said racks being located on adjacent faces thereof, and a hook removable from the base, said hook being provided with means for engaging said racks for progressive movement and also with movable locking means independent of the hook moving means for engaging said smooth portions beneath said racks.

3. A printer's plate holding device comprising, in combination, a base provided with one or more slots in one face thereof, racks projecting inwardly from the opposite side walls of said slots, having smooth surface portions at their under sides, the teeth of said racks being located on adjacent faces thereof, and a hook removable from the base, said hook being provided with an operating gear and a worm gear for engaging the teeth on the adjacent faces of said racks for progressive movement and also with locking means independent of the hook moving means which slide in engagement with the lower sides of said racks.

4. A printer's plate holding device comprising, in combination, a base provided with one or more slots in one face thereof, racks projecting inwardly from the opposite side walls of said slots, having smooth surface portions at their under sides, the teeth of said racks being located on adjacent faces thereof, and a hook provided with an operating gear inclosed by the body of the hook and a worm gear for engaging the teeth on the adjacent faces of said racks for progressive movement and also with locking means independent of the hook moving means and movable relative to the body of the hook for engaging said smooth portions at the under side of said racks. 70
5. A printer's plate holding device comprising, in combination, a base provided with one or more slots in one face thereof, racks positioned on opposite sides of said slots, and a hook provided with means for engaging said racks for progressive movement and also with a rotative locking member adapted to engage beneath said racks. 75
- 10 6. A printer's plate holding device comprising, in combination, a base provided with one or more slots in one face thereof, racks positioned on opposite sides of said slots, and a hook provided with means for engaging said racks for progressive movement and also with rotative locking members at either end of said hook each adapted to be rotated to engage beneath said racks. 80
- 15 7. A printer's plate holding device comprising, in combination, a base provided with one or more slots in one face thereof, racks positioned on opposite sides of said slots, and a hook provided with means for engaging said racks for progressive movement and also with rotative locking members at either end of said hook each adapted to be rotated independently to engage beneath said racks. 85
- 20 8. A printer's plate holding device comprising, in combination, a base provided with one or more slots in one face thereof, racks positioned on opposite sides of said slots, and a removable hook comprising upper and lower portions connected together and provided with means held between said portions for engaging said racks for progressive movement and also with locking means for engaging beneath said racks, said upper and lower portions each extending 90
- 25 55 the full length of the hook body. 95
9. A printer's plate holding device comprising, in combination, a base provided with one or more slots in one face thereof, racks positioned on opposite sides of said slots, and a removable hook comprising a plate engaging member or jaw and a body formed of an upper portion having the jaw integral therewith and a lower portion of a single piece and connected to said upper portion, said upper and lower portions ex- 100
- tending the full length of the hook, said hook also being provided with means held between said portions for engaging said racks for progressive movement and also with locking means for engaging beneath 70
- 10 10. A printer's plate holding device comprising, in combination, a hook and a base provided with one or more slots in the face thereof to receive the hook, overhanging portions at the sides of the slots, at least one of said overhanging portions being provided with teeth constituting a rack at the inner edges thereof and also being provided with a smooth surface at the lower side thereof, said hook being provided with gear means for engaging said rack and for propelling the hook along the slotted portion, and also with locking means which engage smooth surface portions at the lower sides of the overhanging portions. 80
- 15 11. The combination of a base provided with a slotted portion having overhanging portions, and a hook carrying operating means, the shape of the slotted portion, the hook and the operating means being such that the hook and operating means can be lifted vertically from the slot by transverse movement relative to the base, the hook carrying horizontally rotatable locking 90
- 20 means which swings about a vertical axis so as to engage an overhanging portion of the base and hold the hook in place in the slot, said locking means being also capable of being moved relative to the hook so as to permit the hook and operating means to be lifted vertically from the base by transverse movement, the slotted portion having therein a means with which the operating means coöperate when the hook and operating 95
- 25 means are in operative position in the slot. 100
- 30 12. The combination of a base provided with a slotted portion having overhanging portions, and a hook carrying screw operating means, the shape of the slotted portion, the hook and screw operating means being such that the hook and operating means can be lifted vertically from the slot by transverse movement relative to the base, a movable locking means which swing about 105
- 35 a vertical axis and which extends between the hook and base, said locking means being so constructed that in one position thereof the hook will be held in operative position in the slot and so that in another position the hook can be lifted vertically from the slotted portion by transverse movement relative to the base, the slotted portion having therein a rack with which the screw operating means coöperates when the hook 110
- 40 and screw operating means are in operative position in the slot, the locking means being located at the end of the screw member that engages the rack. 115
- 45 13. A printer's plate holding device com- 120
- 50 65 130

prising, in combination, a base provided with one or more slots in one face thereof, racks positioned on opposite sides of said slots, and a removable hook comprising a plate engaging member or jaw and a body formed of an upper portion having the jaw integral therewith and a lower portion of a single piece of metal connected to said upper portion, said upper and lower portions extending the full length of the hook, said hook also being provided with means

held between said portions for engaging said racks for progressive movement and also with separate locking means for holding the hook in place in the slotted portion.

15

Signed in the city, county and State of New York, this 22nd day of April, 1911.

FOLKE W. WESTON.
